UNITED STATES PATENT OFFICE

EDWARD F. HERBERT, OF CINCINNATI, OHIO

VEHICLE UNLOADING CLOSURE AND MOUNTING

Application filed April 12, 1930. Serial No. 443,710.

This invention relates to a movable closure and unloading gate for vehicles such as trucks, furniture vans and the like and has for an object the provision of a gate mounting which permits of a substantially uninterrupted surface connection between the gate and the vehicle bed when the gate is lowered to the plane of the bed.

Another object is to provide a gate mounting of this character which is simple and inexpensive and which requires a minimum of cutting of the bed and gate members.

Another object is to provide a mounting which is of great strength and which provides a sturdy and enduring structure which amply protects the members against wear.

These and other objects are attained by the means described herein and disclosed in the accompanying drawing, in which:

20 Fig. 1 is a fragmental perspective view showing an end portion of a vehicle body and a closure gate connected by means of this invention.

25 Fig. 2 is a sectional view taken on line 2—2 of Fig. 1 but showing the gate in a raised position.

30 Fig. 3 is a sectional view taken on line 3—3 of Fig. 1 but showing the gate member in a depending position.

35 Fig. 4 is a sectional view taken on line 2—2 of Fig. 1.

The gate and mounting of the present invention would normally be provided at the rear end of the vehicle bed and is so described herein. It is to be appreciated however, that the gate and mounting are equally applicable to the sides of the vehicles as well as the end, as is sometimes found desirable in moving vans. In the drawing vehicle bed 5 has mounted upon its top face two or more hinge members 6 each of which comprises a flat metal strap with an integral tubular eye 7 at the end thereof. The vehicle bed 5 is cut away at an angle or chamfered at 8 and its edge is notched slightly as at 80 to accommodate a portion of the eye 7 and a similar eye on a complementary hinge member. The closure gate 9 has its hinged end cut away at an angle or chamfered as at 10. A complementary hinge member 11 is formed of a heavy metal

strap having one portion 12 adjacent the eye extending over the angle face 10 of the gate and the continuation 13 thereof turned about the obtuse angle of the bottom of the gate onto the lower face thereof. It is desirable only for the sake of exterior finish of a fancy vehicle to countersink the hinge member 11 either at 12 or 13 flush with the gate body. At the end of the portion 12 of each hinge member 11 is an eye 14 which also projects beyond the edge 15 of the tail gate. A pin 16 extending through the adjacent pairs of eyes 7 and 14 completes the hinged mounting of the bed 5 and gate 9. It is necessary however to countersink the leaf or hinge member 6 in the top of the bed in the ordinary wooden body construction of trucks. Both the leaf 6 and the leaf 11 are through-bolted by means of bolts 17 and 18 which are suitably countersunk at the top face of the body and gate.

The hinge mounting thus far described is very sturdy and quite simple but, like most other heavy duty hinge mountings provides a gap between the body and gate. The construction of the hinge herein reduces this gap to considerably less than does the ordinary heavy duty hinge, but this space is not small enough, to permit furniture to be rolled from a bed onto the gate without danger of having the legs of the furniture or the casters catch in the opening with a possible resultant damage to the legs of the furniture or the casters thereof. To eliminate the gap between the gate and the body the usual metal wear plates at the adjacent ends of the body and gate are arranged as shown in Fig. 1 wherein the wear plate 19 on the body is secured over the hinge leaves 6 and projects beyond the edge of the body for a distance substantially equal to the actual width of the gap between the body and gate. The eyes 7 and 14 of the complementary hinge members however actually close this gap at intervals so that the projecting edge of the plate is notched as at 20 to receive both of these eyes so that the edge 21 of plate 19 and the eye portions of the hinge members form practically a continuous straight edge. The gate 9 has a wear plate 22 having a straight edge 23 which rides over the edge 21 as the gate is lowered from the

vertical position shown in Fig. 2 to the horizontal position shown in Figs. 1 and 4, where the said edges of the plates contact one another in abutment. The eye portions of the hinge members being round are found to provide negligibly small arcuate projections which are ground away to provide a continuous plane formed by the two plates. Screws 24 retain the plates 19 and 22 upon the bed 10 and gate respectively. These plates are set flush with the top faces of the gate and bed as is customary in structures of this kind.

Any suitable mounting for the bed and means for holding the gate 9 in horizontal position may be employed, these means forming no essential part of the present invention. As indicated in dotted lines at 25 a chain, extending from the body of the vehicle to a pin 26 on the gate may hold the gate in a horizontal unloading position wherein various articles may be dragged or rolled from the bed onto the gate without any difficulty whatsoever.

What is claimed is:

- 25 1. In an unloading closure for vehicles the combination with a vehicle bed and closure gate each chamfered at their adjacent ends, of hinge members secured to the top of the bed and having an eye portion projecting beyond the edge of the bed, complementary hinge members extending over the chamfered edge and bottom of the gate and secured thereto, said hinge members having eyes cooperating with the eyes on the bed hinge members, a pin extending through the eyes and connecting the hinge members, a wear plate covering the bed-hinge members and projecting beyond the edge of the bed, the projecting portion of said plate being notched to receive the eye portions of all of the hinge members, and a straight edge wear plate on the gate arranged to substantially close the notches in the wear plate on the bed when the gate is positioned in the plane of the bed.
- 25 2. In an unloading gate mounting for a vehicle the combination of a vehicle bed and a gate angularly cut away along their adjacent outer edges, substantially flat hinge members mounted on the top of the bed and having eye portions projecting therebeyond, complementary hinge members extending along the cut away edge and bottom of the gate and having eye portions projecting therefrom, a pintle extending through said eye portions and hingedly connecting the gate to the bed whereby said gate may be swung through an angle of 180° to the perpendicular, a wear plate on the top face of the vehicle bed and projecting therebeyond on each side of each pair of hinge eyes, the plate being notched in its overhanging portion to receive the eyes of the hinges, and a second wear plate secured upon the gate and terminating adjacent the top edge of the gate

and cooperating with the notched plate and hinge eyes to form a substantially continuous surface connecting the bed and gate when the gate is positioned in substantial alignment with the bed.

3. In combination a vehicle bed, a gate, hinge members on the bed and gate and each having complementary eye portions extending beyond the respective members to which they are attached, a pintle hingedly connecting the bed and gate members, a wear plate on the gate terminating substantially at the body line of the gate and a wear plate on the bed projecting beyond the bed for a distance substantially equal to the diameter of the projecting hinge eyes, said overhanging portion of the said plate having notches therein into which the hinge eyes extend for closing the notches and forming with the plates substantially an uninterrupted surface when the bed and gate are in a common plane, said mounting permitting movement of the edges of the plate past one another whereby the gate may be moved from an upstanding perpendicular to a depending perpendicular to said bed.

4. In a construction of the class described the combination of a vehicle bed and gate, hinge members secured to said bed and gate and having eye portions projecting longitudinally beyond the bed and gate, a pintle extending through said eyes, a plate mounted flush with the top of the bed and extending therebeyond and notched to receive a portion of each hinge eye above the pintle, whereby the notches are closed, the hinge eyes having flattened portions forming a flush surface with the top of the plate, and a second straight edged plate mounted flush with the top of the gate and having its edge substantially in abutment with the edge of the bed plate when the gate is disposed in a plane with the bed.

5. In a construction of the class described, the combination with a vehicle bed, gate and pintle carrying hinge having its members secured to the bed and gate and connecting the bed and gate at substantially the upper face of the bed and gate, the pintle axis being disposed between the bed and gate when the gate is extended in substantially the plane of the bed, of a plate notched along one of its edges and mounted on the bed and above the hinge member secured to the bed, the notched edge of the plate projecting beyond the pintle and terminating at the adjacent edge of the gate when the gate is extended in the plane of the bed, and the pintle carrying hinge portions lying in and substantially filling the notches in the plate, whereby to provide a substantially smooth continuous surface devoid of recess into which casters, furniture legs and the like may enter, as such articles are moved between and over said bed and gate surfaces.

6. In a construction of the class described, the combination with a vehicle bed, gate and pintle carrying hinge having its members secured to the bed and gate and connecting the 5 bed and gate at substantially the upper face of the bed and gate, the pintle axis being disposed between the bed and gate when the gate is extended in substantially the plane of the bed, of a plate notched along one of its edges 10 and mounted on the bed and above the hinge member secured to the bed, the notched edge of the plate projecting beyond the pintle and terminating at the adjacent edge of the gate when the gate is extended in the plane 15 of the bed, and the pintle carrying hinge portions lying in and substantially filling the notches in the plate, whereby to provide a substantially smooth continuous surface devoid of recess into which casters, furniture legs 20 and the like may enter, as such articles are moved between and over said bed and gate surfaces, the gate when raised above the plane of the bed being adapted for contact along its lower edge, along the plate, inwardly of the 25 notches in the plate, for closing off the notches from the interior of the vehicle.

In testimony whereof, I have hereunto subscribed my name this 10th day of April, 1930.

EDWARD F. HERBERT.
